Application August 5, 1947, Serial No. 766,381

6 Claims. (Cl. 40—115)

1

This invention relates to calendars. It is particularly directed to a perpetual calendar for both Gregorian and Julian systems.

An object of this invention is to provide an improved calendar of the character described comprising a plurality of discs rotatable on a common axis, one of the discs having a window opening through which can be seen a monthly calendar arranged like the usual monthly calendar.

Another object of this invention is to provide a perpetual calendar of the character described which will give monthly calendars on either the Gregorian or Julian systems.

Still a further object of this invention is to provide a perpetual calendar of the character described, which shall be easy to manipulate and easy to read, and which shall be relatively inexpensive to manufacture and practical and efficient to a high degree in use.

Other objects of this invention will in part be obvious and in part hereinafter pointed out.

The invention, accordingly, consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a top plan view of a calendar embodying the invention;

Fig. 2 is a top plan view of the rear disc;

Fig. 3 is a top plan view of next to the rear disc; and

Fig. 4 is a top plan view of the second disc from the top.

Referring now in detail to the drawing, 10 designates a perpetual calendar embodying the invention. The same comprises a top disc 11 formed with a center opening through which there extends an eyelet or other pivot pin 12. Also mounted on the pivot pin 12 is a disc 13 next to the disc 11, a third disc 14 and a rear disc 15. The disc 13 is of greater diameter than the disc 11. The disc 14 is of greater diameter than the disc 13 and the disc 15 is of greater diameter than the disc 14.

The discs 11, 13, 14, 15 may be made of paper, cardboard, synthetic plastic, metal, wood, or any other suitable material. All of the discs are circular and may be rotated independently on the axial pivot pin 12. The discs, of course, are all formed with center holes through which the pivot

2

pins 12 pass. The rear disc 15 is divided by equiangularly spaced radial lines 20, 21, 22, 23, 24, 25, 26 and 27 into eight equal sectors 28, 29, 30, 31, 32, 33, 34 and 35. The radial lines 20 to 27 preferably extend to the outer edge of the disc 15. Each of the eight spaces 28 to 35, respectively, are divided by six equiangularly spaced radial lines 36 into seven equiangular sectors or spaces 37. Of course, the six lines 36 are between a pair of adjacent lines of the lines 20 to 27. Thus, the entire disc is divided by a total of 56 lines into 56 spaces. The number of spaces is a multiple of seven.

Referring now to the space 29, to the right of the second line 36 to the right of line 21, there is marked the numerals "01," "29," "57," "85" arranged radially from the outer end inwardly. The term "to the right" means in this specification—in a clockwise direction. On the left side 15 of said line, next to numeral "29," appears the numeral "28." Also on the left side of said line, next to numeral "57" appears numeral "56." Also on the left side of said line next to numeral "85" appears the numeral "84." It will now be understood that on the left side of said line appear numerals which indicate leap years, whereas, on the right side of the line appear numerals indicating common years. This arrangement is true of all the year numbers as will appear hereinafter. 20 On the right side of the third line 36, to the right of line 21, in space 29 appear the numerals "02," "30," "58" and "86" which are in the same circles as numerals "01," "29," "57" and "85" respectively. To the right of the 4th line 36, to the right of line 21, appear the numerals "03," "31," "59" and "87" arranged in the same respective circles. To the left of line 22, appear the numerals "04," "32," "60" and "88" respectively, arranged on the four concentric circles. On the right side of line 22, appear numerals "05," "33," "61" and "89" arranged on the four respective circles. On the first line to the right of line 22 in space 30, to the right of said line, appear numerals "06," "34," "62" and "90" arranged on the four circles. To the right of second line 36 to the right of line 22, appear numerals "07," "35," "63" and "91" arranged in the same four respective circles.

Also in space 30 to the left of the fifth line 36 to the right of line 22, appear the numerals "08," "36," "64" and "92" arranged in the four concentric circles. To the right of said last mentioned line 36, appear the numerals "09," "37," "65" and "93" on the four respective circles. On the right of the first line 36, to the left of line 23

appear the numerals "10," "38," "66" and "94" on the four respective circles. In space 31 to the right of line 23, appear the numerals "11," "39," "67" and "95" on the four respective circles. To the left of the third line 36 to the right of line 23 appear the numerals "12," "40," "68" and "96" of the four respective circles. To the right of said last mentioned line 36 appear numerals "13," "41," "69" and "97" on the four respective circles. To the right of the 4th line 36 to the right of line 23 appear numerals "14," "42," "70" and "98" on the four respective circles. To the right of the 5th line 36 to the right of line 23 appear numerals "15," "43," "71" and "99" on the four concentric circles.

In space 32, to the left of the first line 36 to the right of line 24 appear numerals "16," "44" and "72" on the outer 3 respective circles. Thus, numerals "16," "44" and "72" are in the same circles as numerals "15," "43" and "71," respectively. To the right of said first line 36 to the right of line 24 are numerals "17," "45" and "73" on the same circles as numerals "16," "44" and "72" respectively.

To the right of the second line 36 to the right of line 24 are numerals "18," "46" and "74" on the three outer circles respectively. To the right of the third line 36 to the right of line 24 are numerals "19," "47" and "75" on the three outer respective circles. On the left of the first line 36 to the left of line 25 are numerals "20," "48" and "76" on the three outer circles respectively. To the right of said last mentioned line 36 are numerals "21," "49" and "77" on the three outer respective circles. To the right of line 25 are numerals "22," "50" and "78" on the three outer respective circles. To the right of the first line 36 to the right of line 25 are numerals "23," "51" and "79" on the three outer circles respectively. To the left of the fourth line 36 to the right of line 25 are numerals "24," "52" and "80" on the three outer circles respectively. To the right of said last mentioned line 36 are numerals "25," "53" and "81" on the three outer circles respectively. To the right of the fifth line 36, to the right of line 25 are numerals "26," "54" and "82" on the three outer circles respectively. To the right of the first line 36 to the left of line 26 are numerals "27," "55" and "83" on the three outer circles respectively.

In space 34 to the left of the first line 36 to the right of line 26 appear radially marked "G2000." The G is on the outermost circle, that is, on the same circle as the numeral "27." To the right of said first line 36 to the right of line 26 also arranged radially from the outer end inwardly, is the notation "G1900" aligned with the notation "G2000." To the right of the third line 36 to the right of line 26 appears the notation "G1800" similarly arranged. To the right of the fifth line 36 to the right of line 26 appears the notation "G2100" similarly arranged. The G's in space 34 indicate Gregorian calendar system as will appear hereinafter.

In space 35 on the left of the first space 36 to the right of line 27 radially arranged from the outer end inwardly appears the notion "J1900," arranged similar to "G2100." To the left of the second line 36 to the right of line 27 appears the notation "J1800" similarly arranged. To the left of the third line 36 to the right of line 27 appears the notation "J1700." To the left of the fourth line 36 to the right of line 27 appears the notation "J1600." To the left of the 5th line 36 to the right of line 27 appears the notation

"J1500." To the left of the sixth line 36 to the right of line 27 appears the notation "J2100" similarly arranged. To the left of line 20 appears the notation "J2000," similarly arranged. The "J" in space 35 indicates Julian calendar system.

The lines and numerals may, of course, be printed, engraved or embossed or otherwise marked in any suitable manner on the disc 15.

10 The disc 14 overlies the disc 15 and is of somewhat smaller diameter so that an outer circular portion of disc 15 is exposed. In said exposed portion of the back disc 15 can be seen the outer ends of lines 20 to 27, respectively. The disc 14 is divided by eight equiangular spaced radial lines 40 to 47 respectively into eight equiangular spaces 48 to 55 respectively. Each of the spaces 48 to 55 is divided by six equiangularly spaced lines 56 into seven equiangular spaces 57. 20 Thus, the disc 14 is likewise divided into fifty-six equiangular spaces 57.

25 The disc 14 is formed with a radial window opening 60 located between the 1st and 2nd lines 56 to the right of line 41. The radial position of opening 60 is such that it would uncover marking "J2000." It would also uncover numbers on disc 15 located on the four respective circles aforementioned. Adjacent the inner edge of window opening 60 appears the notation "Apr." 30 Between the fifth and sixth lines 57 to the right of line 42 is a radial opening 61 located similarly, with respect to the center of the disc, as window opening 60. At the inner end of the opening 61 is the notation "Feb L" meaning February leap year. 35 Between the fourth and fifth lines 56 to the right of line 44 is a window opening 62 similarly spaced radially, to window opening 61. At the inner end of window opening 62 is the notation "Feb C" meaning February common year 40 (not a leap year).

45 Between the second and third lines 56, to the right of line 46 is a window opening 63, similarly spaced to window openings 60, 61 and 62 with respect to the center of the disc. At the inner end of window opening 63 is the notation "Dec." Between the third line 56 to the left of line 47 and the second line 56 to the right of said line 47, is a window opening 64. The window opening 64 has an angular extent equivalent to five spaces

50 57. Its radial position relative to the center of the disc is the same as the opening 63. At the inner edge of opening 64 and between the third and second lines 56 to the left of line 47 is the notation "Mar." Also at the inner edge of the 55 window opening 64, between the line 47 and the first and second lines 56 to the left of line 47 is the notation "Aug." Between the first line 56 to the left of line 47 and at the inner edge of window 66 is the notation "May." Between said 60 line 47 and the first line 56 to the right of said line 47 and at the inner edge of the window opening 64 is the notation "Oct." and also "Ja-C." The notation "Ja-C" means January, common. Between the first and second lines 56 to the right of line 47 and at the inner edge of said window opening 64 is the notation "July" and also "Ja-L," the latter meaning January, leap year.

65 Disc 14 is also formed with a window opening 65 located between the second line 56 to the right of line 40 and the second line 56 to the left of line 41. Window opening 65 thus has an angular extent equivalent to three spaces 57. Its radial position is similar to opening 60. At the inner edge of window opening 65, and between the second and third lines 56 to the right of line 40, is

the notation "Sept." Between the third and fourth lines 56 to the right of line 40 and at the inner edge of window 65 is the notation "Jun" for June. Between the fourth and fifth lines 56 to the right of line 40, and the inner edge of window opening 65 is the notation "Nov."

It will be noted that the outer peripheral portion 68 of disc 14 may be seen beyond disc 13. On said exposed peripheral portion and in alignment with window 60 is marked the notation "Apr." which is, of course, radially aligned with the first mentioned notation "Apr." Said peripheral portion 68 is also marked with the notations "Feb.-1," "Feb.-c," "Dec.," "Mar.," "Aug.," "May," "Oct.," "Ja-c," "July," "Ja-1," "Sept.," "June" and "Nov.," in radial alignment with the corresponding notations on disc 14.

The disc 14 is also marked with eight sets of spirally arranged numbers. Each set of numbers begins at one of the lines 40 to 47 and extends therefrom spirally inwardly in a clockwise direction. Each set of spirally arranged numbers nests within the next sets of numbers. The eight sets of numbers referred to are on the portion of the disc inwardly of the windows 60 to 65. Thus, beginning with line 40, it will be noted that to the right of said line, appears number "1" in space 57. In the next space, 57, appears numeral "2." The numbers are arranged successively and spirally inwardly and extend to number "28." Also, to the right of line 41 appears the number "1" radially positioned similar to the first mentioned numeral, and the set of numbers started there also goes to "28." However, number "8" of the first set appears below number "1" of the second set. The set of numbers beginning at line 42 goes to "31." The set of numbers beginning at line 43 also goes to "31." The set of numbers beginning at 44 goes to "30." The set of numbers beginning at 45 goes to "30." The set of numbers beginning at 46 goes to "29." The set of numbers beginning at 47 goes to "29."

It will now be understood that in each space 57, is a column of numbers arranged radially and each number is seven greater than the next outer number in said column. Thus, the column of numbers in the space 57 to the right of line 40 are "1," "8," "15," "22," "29." In the next column to the right, the numbers of "2," "9," "16," "23," "30," like in an ordinary monthly calendar.

Referring now to disc 13 which overlies disc 14, the same is formed with a radial window opening 70 having an outer edge 71 which has the same radius as the outer edge of the window openings 60 to 65. The angular width of window opening 70 is the same as the angular extent of one of the spaces 57 of disc 14 or a space 37 of disc 15. The side edges 72 of window 70 are radial. The inner edge 73 of window 70 has a radius of curvature which would locate it between the notations of the months at the inner edges of the window openings 60 to 65 of disc 14 and the spirally arranged numbers on said disc. Thus, when window opening 70 registers with window opening 60, the entire window opening 60 and the notation Apr. at the inner edge thereof would be seen therethrough.

The disc 13 is formed with another arcuate window opening 75 having an outer arcuate edge 76 of a radius of curvature which would locate it just beyond the spirally arranged numbers on disc 14. It has an inner arcuate edge 77 having a radius of curvature which would locate it just inside of the spirally arranged numbers on disc

14. Said window opening 75 has radial side edges 78. The angular extent of window opening 75 is equivalent to thirteen spaces 37 or 57. Thus, through the window opening 75 there would be exposed thirteen radial spaces 57 on disc 14 and all the spirally arranged numbers in columns in those thirteen spaces.

Overlying the disc 13, is the top disc 11. Said top disc 11 is formed with a window opening 80 having an outer arcuate edge 81 of the same radius of curvature as the outer edge 71 of the window opening 70 in disc 13. It has an inner arcuate edge 82 having the same radius of curvature as the inner edge 73 of said window opening. It has radial side edges 83, and the angular extent of the window opening is equivalent to seven spaces 37 or 57.

Said disc 11 is furthermore formed with a window opening 90 having outer and inner arcuate edges 91 and 92, which register with the outer and inner arcuate edges 76 and 77 of the window opening 75. Said window opening 90 has radial side edges 93 and the angular extent of said window opening is equivalent to seven spaces 37 or 57. Thus, the edges 93 and 83 are aligned with each other.

The disc 11 is marked adjacent the edge 81 with the numbers "18," "17," "16," "15," "21," "20," "19," "18" arranged successively and spaced apart by the width of one of the spaces 57. Thus, numerals "18" are aligned with edges 83 as shown in the drawing. Disc 11 is furthermore formed adjacent its outer edge with the following numbers successively arranged, "19," "18," "21," "20." Numeral "19" is aligned with the left edge 83. Numeral "18" is aligned with numeral "16" adjacent edge 81. Thus, the spaces between numerals "19" and "18" are equivalent to two spaces 57. Numeral "21," adjacent the outer edge of the disc 11 is aligned with numeral "21" adjacent edge 81. Numeral "20" adjacent the outer edge of the disc is aligned with numeral "19" adjacent edge 81.

The disc may be furthermore marked adjacent the outer edge thereof with the notation "cycle 400 years, Gregorian." Said disc may also be marked adjacent its outer edge with the following notice "Gregorian, since October 15, 1582." The disc may also be marked on the same circle as numerals "18," "17," "16," "15," "21," "20," "19" and "18" with the notations "cycle 700 years, Julian" and "Julian, since January 1st, 46 B. C." The disc 11 may also be marked with notations, "Sun.," "Mon.," "Tue.," "Wed.," "Thur.," "Fri." and "Sat." at the strip between the window openings 80 and 90. Said notices are aligned with the seven columns of figures which can be seen through the window opening 90. Thus, a complete monthly calendar can always be seen through the window 90. Through the window 80 can always be seen the window 70.

The method of finding the correct monthly calendar for any month on either Gregorian or Julian systems with the improved calendar embodying the invention will now be described.

Disc 13 is first moved to bring window opening 70 in registry with the desired monthly notation on disc 14. This window opening will be made to register either with window opening 60, 61, 62 or 63 or with some division of window openings 64 or 65 so that through the window opening 70 will be seen the desired month. The disc 11 is held in such position that some portion of the window opening 80 registers with the window

opening 70. When the proper month is registered with window opening 70, the three discs 11, 13 and 14 may be rotated together until the proper year number on disc 15 is seen through the window 70. Of course, the numbers on disc 15 give the year in the century and do not give the century years except for the years 1800, 1900, 2000 and 2100 on the Gregorian system or the years 1500, 1600, 1700, 1800, 1900, 2000, 2100 on the Julian calendar. If the year selected is a leap 10 year, the radial line on disc 15 to the right of said leap year is registered with the radial edge at the right of window opening 70. If the year selected is a common year, then the radial line to the left of said year is registered with the left 15 radial edge of the window opening 70.

When the proper alignment has been made, then discs 13, 14 and 15 are held together and the top disc 11 is moved to bring the proper century number in alignment with the nearest of the 20 lines 20 to 26 on disc 15. By the century numbers is, of course, meant Gregorian century numbers on disc 11, adjacent its outer peripheral edge and Julian century numbers on disc 11 adjacent edge 81.

When the discs are so set, a complete monthly calendar for the month and year selected will be seen through the window opening 90. For centuries other than 18th to 21st, on the Gregorian calendar, the century selected would be one that differs by four or multiples of four. Thus, if the 24th century on the Gregorian calendar is desired, the 20th century on the disc 11 is used, the reason being, of course, that the Gregorian calendar repeats itself every 400 years. For the Julian calendar, the same is true, except that the calendar repeats itself every 700 years. For Gregorian years, 1800, 1900, 2000 and 2100, the corresponding years in space 34 of disc 15 are used. Under the Julian system for the years 1500, 1600, 1700, 1800, 1900, 2000 and 2100, the corresponding year numbers on space 35 are used. Of course, for all other century years, corresponding numbers on spaces 34 and 35 are used. Thus, for a Gregorian year 2400, the "G2000" will be used in space 34. Under the Julian calendar for the year 1000 the "J1700" would be used in space 35.

Taking a case in point, let us suppose that it is desired to find the monthly calendar for July, 1947. Disc 13 is moved to bring window 70 in alignment with the portion of window 64 which is marked July. The two discs 14 and 13 are then moved together until the line to the left of numeral "47" on disc 15 registers with the left edge of window 70. Numeral "19" at the outer peripheral edge of disc 11 is then moved in registry with line 24 of disc 15. When that is done it will be noted that a month calendar will be seen from window 90 showing the "1" to be a Tuesday and the calendar going to "31." For the month of February care must be taken to select either "Feb.-L" or "Feb.-C" on disc 14. Also for January care must be taken to either select "J-L" or "J-C" on disc 14.

It will be noted that the window opening 75 on disc 13 is equivalent to 13 radial spaces. Thus, the century number on disc 11 must be aligned either with the line 20 to 27 on the left or the right of the year selected and appearing on disc 15, whichever will show seven full spaces through the window 90.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A perpetual calendar comprising four discs, means to mount said discs for rotation about a common axis, the rear disc being marked with year numbers, the disc in front of the rear disc being formed with window openings adapted to expose said year numbers, said last mentioned disc being furthermore formed with spirally arranged day-in-month numbers, and with month indication the disc in front of the last mentioned disc being formed with a window opening adapted to register with the window openings in said disc in front of the rear disc and with selected ones of the month indications on the disc in front of the rear disc, and also formed with a window opening adapted to register with the day-in-month numbers, and a front disc having a window opening adapted to register with the first window opening in the disc in back of the front disc, and also formed with the second window opening adapted to register with the second window opening in said disc in back of the front disc and the days of the week being marked on the front disc in the space between the two window openings of the front disc.

2. A perpetual calendar comprising four discs, means to mount said discs for rotation about a common axis, the rear disc being marked with year numbers, the disc in front of the rear disc being formed with window openings adapted to expose said year numbers, said last mentioned disc being furthermore formed with spirally arranged day-in-month numbers, and with month indications the disc in front of the last mentioned disc being formed with a window opening adapted to register with the window openings in said disc in front of the rear disc and with selected ones of the month indications on the disc in front of the rear disc, and also formed with a window opening adapted to register with the day-in-month numbers, and a front disc having a window opening adapted to register with the first window opening in the disc in back of the front disc, and also formed with the second window opening adapted to register with the second window opening in said disc in back of the front disc and the days of the week being marked on the front disc in the space between the two window openings of the front disc, the back disc being of greatest diameter, next to the back disc being of smaller diameter, the disc in front of that disc being of still smaller diameter, and the front disc being of still smaller diameter.

3. A perpetual calendar comprising four discs mounted for independent rotation about a common pivotal axis, the front disc being formed with a pair of arcuate radial aligned window openings, the disc behind the front disc being formed with a pair of window openings of different angular extent but positioned radially similar to the two window openings in the front disc, respectively, the disc in front of the rear disc being formed with a plurality of window openings radially positioned similarly to one of the window openings in the front disc, and being marked with spirally arranged sets of day-in-month numbers, so located that they may be seen

through the other window opening of the front disc, and said rear disc being provided with year numbers which may be selectively seen through registering window openings in the first three discs.

4. A perpetual calendar comprising four superimposed discs mounted for independent rotation about a common pivotal axis, the rear disc being divided into a number of equiangular radial spaces comprising a multiple of 7, and bearing numbers designating year in century in various of said spaces, said numbers being arranged in radial columns in said spaces, the disc next to the rear disc being formed with window openings adapted to expose selected columns of numbers on the rear disc, said window openings being marked to designate a month for each portion of window opening corresponding to a radial space, said disc in front of the rear disc being marked with nesting radially arranged spiral sets of numbers designated day-in-month, the spiral starting point of each set being seven radial spaces away from the starting point of adjacent sets, the disc behind the front disc being formed with a window opening having an angular extent equivalent to one radial space and adapted to register with window openings with the disc in front of the rear disc, said disc behind the front disc being further formed with an arcuate window opening having a radial extent equivalent to 13 radial spaces and adapted to uncover day of month numbers in said sets, the front disc being formed with an arcuate window opening having an angular extent being equivalent to seven radial spaces, and said window opening being positioned radially similarly to the first window openings in the disc behind the front disc, said front disc being formed with a second window opening having an angular extent similar to the angular extent of said first window opening in the front disc, and the radial position of said second window opening in the front disc being such as to expose seven columns of day-in-month numbers in the disc in front of the rear disc.

5. A perpetual calendar comprising four superimposed discs mounted for independent rotation about a common pivotal axis, the rear disc being divided into a number of equiangular radial spaces comprising a multiple of 7, and bearing numbers designating year in century in various of said spaces, said numbers being arranged in radial columns in said spaces, the disc next to the rear disc being formed with window openings adapted to expose selected columns of numbers on the rear disc, said window openings being marked to designate a month for each portion of window opening corresponding to a radial space, said disc in front of the rear disc being marked with nesting spiral radially arranged sets of numbers designated day-in-month, the spiral starting point of each set being seven radial spaces away from the starting point of adjacent sets, the disc behind the front disc being formed with a window opening having an angular extent equivalent to one radial space and adapted to register with window openings with the disc in front of the rear disc, said disc behind the front disc being further formed with an arcuate window opening having a radial extent equivalent to 13 radial spaces and adapted to uncover day in month numbers in said sets, the front disc being formed with an arcuate window opening having an angular extent being equivalent to seven radial spaces, and said window opening

being positioned radially similarly to the first window opening in the disc behind the front disc, said front disc being formed with a second window opening having an angular extent similar to the angular extent of said first window opening in the front disc, and the radial position of said second window opening in the front disc being such as to expose seven columns of day-in-month numbers in the disc in front of the rear disc, the rear disc having the greatest diameter, the disc in front of the rear disc having the next smaller diameter, the disc behind the front disc being still smaller in diameter, and the front disc being smallest in diameter.

15 6. A perpetual calendar comprising four superimposed discs mounted for independent rotation about a common pivotal axis, the rear disc being divided into a number of equiangular radial spaces comprising a multiple of 7, and bearing numbers designating year in century in various of said spaces, said numbers being arranged in radial columns in said spaces, the disc next to the rear disc being formed with window openings adapted to expose selected columns of numbers on the rear disc, said window openings being marked to designate a month for each portion of window opening corresponding to a radial space, said disc in front of the rear disc being marked with nesting spiral radially arranged sets of numbers designated day-in-month, the spiral starting point of each set being seven radial spaces away from the starting point of adjacent sets, the disc behind the front disc being formed with a window opening having an angular extent equivalent to one radial space and adapted to register with window openings with the disc in front of the rear disc, said disc behind the front disc being further formed with an arcuate window opening having a radial extent equivalent to 13 radial spaces and adapted to uncover day in month numbers in said sets, the front disc being formed with an arcuate window opening having an angular extent being equivalent to seven radial spaces, and said window opening being positioned radially similarly to the first window opening in the disc behind the front disc, said front disc being formed with a second window opening having an angular extent similar to the angular extent of said first window opening in the front disc, and the radial position of said second window opening in the front disc being such as to expose seven columns of day-in-month numbers in the disc in front of the rear disc, the rear disc having the greatest diameter, the disc in front of the rear disc having the next smaller diameter, the disc behind the front disc being still smaller in diameter, and the front disc being smallest in diameter, the disc in front of the rear disc being marked adjacent its periphery with monthly designations in alignment with the window openings therein, the portion of the front disc between the window openings therein being marked to indicate successively the days of the week from Sunday to Saturday.
